UNITED STATES PATENT OFFICE.

FRANK A. SEIBERLING AND CLINTON H. KNECHT, OF AKRON, OHIO,
ASSIGNORS TO J. F. SEIBERLING & CO., OF SAME PLACE.

GRAIN-BINDER.

SPECIFICATION forming part of Letters Patent No. 496,797, dated May 2, 1893.

Application filed April 27, 1892. Serial No. 430,909. (No model.)

To all whom it may concern:

Be it known that we, FRANK A. SEIBERLING and CLINTON H. KNECHT, citizens of the United States, residents of Akron, county of Summit, and State of Ohio, have invented a new and useful Improvement in Grain-Binders, of which the following is a full, clear, and exact description, reference being had to the accompanying drawings, making part of this specification.

Our invention relates to that class of grain binders employing a "needle trip," or means connected with and operating through the needle to trip and release the binder mechanism, and requiring, for this purpose, a yielding pitman which will allow the needle shaft and needle, when the latter is in position to receive the grain, to vibrate sufficiently to release and set the binder mechanism in motion.

The object of the invention is to produce a simple, effective and inexpensive construction of trip of the kind referred to and also to improve the grain compressing devices and bring them into compact and effective arrangement; it will be understood from the following description and claims, reference being had to the drawings, in which—

Figure 1 represents a vertical section through the binder, showing the needle, one packer and the compressor mechanism in side elevation and in position to receive the grain. Fig. 2 is a similar view with the parts in position for compressing the grain for binding, &c., and Fig. 3 also a similar view of the parts after the binding has been completed and the bundle is free to be discharged from the machine. Figs. 4, 5, 6, 7, 8, 9, 10 and 11 show, in detail, parts of the machine, hereinafter referred to, detached. Fig. 12 is a plan view, partly in section, with the binder table broken away and the compressor removed to show other parts. Fig. 13 is a front elevation showing the arrangement of the needle actuating mechanism and of the devices for tripping the same, and Fig. 14 is a similar view of the needle shaft crank-arm, pitman, &c., showing said parts in a different position from that shown in Fig. 13.

The binder frame is composed of the longi-

tudinal sills A, A', transverse sills A², A³ and A⁴ and the lower longitudinal sleeve B' of the U-shaped binder gear standard B, said sleeve being connected with the inner ends of the sills A² and A³, and through the latter with the sill A. The sill A' forms an extension of the frame beyond the sleeve B' and is united to the sill A⁴ and through the latter to the outer sill A, the parts referred to forming a strong, rectangular frame, upon which the binder table C is supported in any usual manner.

The sleeve B' extends a short distance beyond the intermediate transverse sill A³ and has the needle shaft D journaled in it and upon this shaft the needle D' is secured, adjacent to the end of the sleeve and intermediate the sills A³ and A⁴, as shown in Fig. 12. The shaft D extends beyond the needle and may be further journaled in the sill A⁴ or in the sleeve or plate B² secured thereon and to the sill A'.

The sill A³, shown in side view, Fig. 4, and plan view, Fig. 5 is provided at its outer end with a socket at a, for the sill A; intermediate its ends with a pendent bearing sleeve a' in which the packer shaft is journaled and near its inner end, is bolted to lugs on the sleeve B', through a horizontal flange on its upper edge. The sill extends beyond the point of attachment to the sleeve B' and is provided on said extension with a stud or pivot for one of the packer links and below the latter, at its end, with a depressed bearing sleeve for the vibrating bridge, as will appear.

The needle D' has a heel extension beyond its shaft D and to this extension the bifurcated end e' of a compressor bar e, is pivoted. The form of this bar is shown in plan view Fig. 6; it is provided in its bifurcated end with a pendent perforated ear e² in which a set screw e³ is secured forming an adjustable stop acted upon by a pendent spur d, on the needle for restoring the bar e to and holding it in operative position as will appear. Intermediate its ends the bar e is provided with a stud pivot e⁴ on which a roller f is mounted.

g is a compressor frame made in form substantially as shown in detail views, Figs. 7, 8 and 9, having two upright sides which em-

brace the bar e , between them and are united by a horizontal flooring which extends beyond the rear, upright part in the form of a ledge g' provided with a pin or extension g^2 for a purpose which will appear. The inner end of the frame g is provided on one side with a flange g^3 , perforated to receive a bolt h passing through the base of the fork on the end of the bar e , the head of the bolt resting in 5 said fork, as shown. The bolt h , outside of the flange g^3 is surrounded by a spiral spring h' , the tension of which is regulated by a nut h^2 , adjustable on the outer end of the bolt, and is exerted to hold the frame g against the 10 forked end of the bar e . The outer end of the spring h' and bolt h are upheld by the ledge g' and a loop g^4 on the outer end of the frame g . Above the loop g^4 is a friction roller g^5 journaled in the upright sides of the frame g 15 and resting and rolling on the bar e and inward from said roller. The side plates are provided with a pin or bolt at i on which the compressor I is mounted, said compressor being provided at i' (Fig. 11) with two or more 20 perforations permitting its adjustment on the pin i , to regulate the size of the bundle. 25

The foot of the compressor rests and slides, with the frame g on the bar e and above the plane of the pivot and in rear thereof, the 30 compressor is provided with horizontal lips or flanges i^2 which rest on the upper edges of the sides of the frame g and serve to uphold the compressor against the backward thrust of the grain.

35 The side of the compressor frame g adjacent to the roller f , is cut away at g^6 to permit it to pass said roller, sufficiently to allow the inner end of said frame to abut or be drawn against the shoulders of the fork of 40 the bar e .

To the inner pendent sleeve a^2 of the sill A^3 is pivoted an upright arm J , shown in rear elevation in Fig. 10, the upper end of which underlies the roller f and is provided with a 45 ledge j , V-shaped on its lower face and upon which said roller descends when the compressor bar e is forced downward by the pressure of the grain. Inward from said arm, which constitutes what we term the "vibrating 50 bridge," the sill A^3 has a flange or ledge a^3 , formed on its slightly curved or inclined downward on its end adjacent to the bridge J and outside of and below said ledge the sill is provided with stops or spurs a^4 and a^5 , between 55 which an arm j' on the bridge J extends, said stops serving to limit the extent of vibration of the bridge, which is upheld in its normal, upright position by means of a spring j' , secured to the sill A^3 .

60 The sill A^3 is further provided at a^6 with a pin or stud on which the link k of the packer K adjacent to said sill, is pivoted, and, on its lower edge with a horizontal arm or stop a^7 , which projects under the compressor frame 65 e and limits its downward movement.

To the frame sill A is secured a sleeve L provided with two rods or long fingers l , l ,

which extend up through the needle slot in the table, one on each side of the needle and across the table, and the forward one of these, 70 overlying the roller f is provided with a pendant spur l' , which, when the compressor and compressor bar e and roller f are in their normal position, rests on said roller and upholds the outer ends of the rods l above the binder 75 table, as shown in Fig. 1.

The compressor is upheld in position to receive the grain, by means of the spur d on the needle abutting against the stop or set screw e^3 on the compressor frame and the grain being forced against the compressor and back on the rods l , by the packers K , K , acting in the usual manner, when enough has accumulated to form a bundle, the pressure of the grain outward on the compressor and downward on the rods l , is sufficient to depress the bar e , overcoming the resistance of the needle and vibrating the latter and its shaft sufficiently to release and set in motion the binder mechanism, as will appear. 90

To the forward end of the needle shaft D is secured a crank arm D^2 from which a pitman extends to a crank pin on a bevel gear M on the knotted actuating shaft and from which a vibratory movement is imparted to 95 the needle shaft in a well known manner. Motion is communicated to the gear M through the shaft M' and suitable connecting bevel pinions from a bevel gear M^2 on the packer shaft K^2 . The shaft K^2 has a continuous rotary motion imparted to it in any usual manner and on its forward end has a cross head k^2 provided with rearwardly projecting pins carrying friction rollers k^3 . The gear M^2 is loose on the shaft K^2 and is provided with a 100 dog k^4 , having a spur held, normally, in engagement with one of the rollers k^3 for engaging the gear M^2 with its shaft, in any well known manner.

The crank arm D^2 is provided with a trip arm D^3 , which, as the needle approaches its position of rest to receive the grain, comes in contact with the projecting arm of the dog k^4 and throwing the latter out of engagement with the shaft K^2 , trips the binder mechanism and allows the latter to rest until enough grain has accumulated to form the bundle and the pressure thereof acts on the needle as explained, to vibrate it, and the arm D^2 and raise the latter to release the dog k^4 and 110 set the binder gearing again in motion. To permit this vibration of the needle shaft and arm D^2 , it is essential that the pitman connecting the needle shaft with its actuating crank, should be adapted to yield and to this end the pitman is jointed at or near the center of its length, one part m thereof being provided with a short rigid arm m^2 overlying and extending beyond the hinge connecting it with the part m' and forming a stop to 115 make the pitman rigid in one direction. The part m' is perforated, near the hinge to receive a bolt n , which passes through the arm m^2 and outside thereof is surrounded by a 120

spring n' and a nut n^2 , by adjusting which, the tension of the spring can be adjusted as desired.

Below the joint in the hinge, the part m is provided with a threaded nut or perforation at o , to receive a set screw o' , which is so adjusted as to come in contact with the crank arm D^2 near the needle shaft, just before the needle reaches its position of rest, thereby 5 breaking the joint in the pitman, as shown in full lines, Fig. 13, deflecting said pitman from the right line, shown in dotted lines 1. As pressure is brought by the grain on the compressor and through the latter on the needle, 10 as above explained, the pitman is still farther deflected, assuming the position shown in dotted lines 2, Fig. 13, thus allowing the arm D^3 to be rocked up out of the way of the dog k^4 , releasing the latter and allowing it to engage the bevel gear M^2 with its shaft K^2 and thus to set the binder mechanism in motion. The set screw o' , instead of being on the pitman, may be applied to the crank arm D^2 , as shown in Fig. 14, with the same result.

25 The packer shaft and packers are of a well known form, one of the packer links k , being pivoted to a pin on the sill A^3 as explained. The other packer link k' is pivoted to an arm b on the sleeve or plate B^2 and the latter 30 is also provided with a pendent lug, shown at p (in dotted lines Fig. 12) to which one end of a link p' is connected, the other end of said link being connected to a link p^2 , which at its outer end is connected to a pendent arm p^3 , secured to a hinged, leaf extension C' of the binder table.

The operation, beyond what has already been described, is as follows:—Supposing the parts to be in the position shown in Fig. 1, 40 the grain is carried in by the packers against the compressor I until the pressure on the latter and on the rods l , forces the compressor bar e downward, until the roller f rests on and is upheld by the upper end of the vibrating bridge or arm J . By this movement the needle is vibrated and the dog k^4 released, when the binder mechanism is set in motion as explained. As the needle is now farther vibrated, the bar e and the compressor frame 45 g through their connection with the needle, are drawn forward, carrying the compressor toward the needle and the bridge J , supporting it, is carried inward as shown in Fig. 2, by the roller f , until the latter reaches and is 50 drawn on and supported by the ledge a^3 . This releases the bridge J which is immediately retracted by the spring to its normal position. When the needle starts back to receive a new bundle, the roller f drops off the ledge a^3 , and falling down between the ledge and the bridge J , allows the compressor frame and bar to drop down on the stop a^7 , the parts 55 assuming the position shown in Fig. 3. The links p', p^2 , upholding the hinged leaf C' of the binder table, are supported in the position shown in Fig. 1, for that purpose, by the pin g^2 on the compressor frame g , and as the lat-

ter descends, the toggle link p', p^2 , is left unsupported and the leaf C' falls into the horizontal position shown in Fig. 3, thereby leaving the binder table clear, outside the bundle, for the free discharge of the latter, after which, in the farther descent of the needle, the spur d acts on the stop d^5 on the compressor bar, vibrating the latter upward and with it 70 the compressor frame and compressor to their normal position shown in Fig. 1. The roller f , in rising, comes in contact with the outer, upwardly inclined, lower face of the ledge j on the arm or bridge J and crowds the latter 75 inward until the roller passes from under the ledge, when the spring j' restores the bridge to position to again receive and carry the roller inward. In this return movement of the compressor mechanism, the pin g^2 acts on 80 the link p' and through the latter on the leaf C' to raise it to the upright position shown in Fig. 1. The spring h' lies substantially parallel with the bar e and allows the compressor to yield outwardly, under the pressure of the grain, thereby increasing the leverage of the compressor for depressing said bar. The operation of the other parts will be readily understood.

Having thus described our invention, what 95 we claim as new, and desire to secure by Letters Patent, is—

1. The combination in a grain binder, of the compressor bar connected to the needle shaft to be moved thereby, and a vibrating bridge or arm pivoted to a fixed support and vibrated by said bar resting thereon to carry the compressor in its operative throw or movement, substantially as described.

2. The combination in a grain binder, of 105 the compressor supporting bar connected to the needle shaft to be moved thereby, a supporting arm or bridge therefor pivoted to a fixed support and vibrated by said compressor bar resting thereon to carry the compressor 110 in its operative movement, and a fixed support for receiving the bar from said bridge, substantially as described.

3. The combination with the compressor supporting bar, of a vibrating arm or bridge 115 pivoted to a fixed support and vibrated by said bar resting thereon to carry the bar in the operative movement of the compressor, a spring for retracting said bridge when released from said bar, and a fixed support for receiving and upholding the compressor while the bridge is being retracted to its normal position, substantially as described.

4. The combination with the compressor supporting bar, of an arm or bridge pivoted 125 to the binder frame and vibrated by said bar resting thereon to carry the compressor in its operative movement, stops for limiting the throw of said bridge, and a stationary ledge for upholding said bar when the bridge is withdrawn, substantially as described.

5. The combination with the needle of the compressor bar e pivoted to said needle and provided with a friction roller f , the com-

pressor-frame and compressor carried thereby, the spring h' connecting said compressor frame and bar and acting on said compressor and the vibrating bridge J and ledge a^3 for supporting said bar and compressor, substantially as described.

6. The compressor supporting bar connected to the needle shaft to be vibrated thereby and the compressor frame sliding on said bar 10 and carrying the compressor, in combination with the spring connecting said frame and bar, arranged and operating substantially as described.

7. The combination with a compressor supporting bar carrying the compressor frame and compressor and connected to the needle shaft to be vibrated thereby, and provided with a carrying roller f , of a bridge J pivoted to the frame to vibrate with and carry said 15 bar in the operative movement of the compressor, the stationary receiving ledge a^3 , and the stops a^4 , a^5 , for limiting the lateral movements of said bridge, substantially as described.

25 8. The compressor supporting bar provided with the carrying roller, and the pivoted bridge supporting said roller and vibrating laterally to carry the compressor in its operative movement, in combination with the compressor 30 frame sliding on said bar and provided with a friction roller at its heel end resting and moving on said bar, whereby the movement of the compressor is facilitated and the ledge for receiving the compressor bar from the 35 bridge, substantially as described.

9. The combination with the compressor bar e , of the compressor frame g , compressor spring h' , the rod h passing through said spring and connected at its forward end to said bar 40 e and a support on the compressor frame for the rear or outer end of said rod and spring, substantially as described.

10. The frame sill A^3 provided at its rear or outer end with a bearing for and in combina-

tion with the laterally vibrating bridge J, the 45 compressor supporting bar carried by said bridge in the operative movement of the compressor, and the stationary ledge a^3 , for receiving said bar from said bridge, substantially as described. 50

11. The combination with the binder frame sill A^3 , of the vibrating bridge J, the compressor supporting bar, carried by said bridge in the operative movement of the compressor, stationary ledge a^3 , receiving the bar from said 55 bridge, the compressor rest or stop a^7 and packer link k , all connected with the outer end of said sill, substantially as described.

12. The combination with the vibrating crank arm D^2 on the needle shaft and the 60 crank wheel M on the knotter actuating shaft, of the pitman connecting said wheel and arm, provided with a hinge joint at or near the center of its length permitting its being flexed, substantially as and for the purpose de- 65 scribed.

13. The jointed pitman for actuating the needle shaft, consisting of the two parts m and m' , one of which is provided with a stop arm m^2 overlying the other part, in combination with 70 the bolt n , spring n' and means for adjusting the tension of said spring, substantially as described.

14. The combination with the needle shaft and needle of the jointed pitman m , m' , provided with the tension spring n' , the adjustable stop o , operating on said pitman, the crank wheel M operating said pitman, the trip arm D^3 , the dog k^4 and the compressor connected with the needle shaft, substantially as 80 described.

In testimony whereof we have hereunto set our hands this 25th day of April, A. D. 1892.

FRANK A. SEIBERLING.
